UNITED STATES PATENT OFFICE.

DAVID FELIX BRODERICK, OF NEW BRITAIN, CONNECTICUT, ASSIGNOR OF
ONE-HALF TO LEWIS SPERRY, OF SOUTH WINDSOR, CONNECTICUT.

DIPPING MECHANISM FOR ELECTROPLATING APPARATUS.

No. 839,719.

Specification of Letters Patent.

Patented Dec. 25, 1906.

Application filed July 27, 1906. Serial No. 328,070.

To all whom it may concern:

Be it known that I, DAVID FELIX BRODERICK, a resident of New Britain, in the county of Hartford and State of Connecticut, have invented certain new and useful Improvements in Dipping Mechanism for Electroplating Apparatus; and I do hereby declare the following to be a full, clear, and exact description of the invention, such as will enable others skilled in the art to which it appertains to make and use the same.

My invention relates to dipping mechanism adapted particularly for use in electroplating apparatus, one object of the invention being to provide means for automatically dipping the articles to be plated successively into the various plating and washing baths.

A further object is to so construct a continuously-operating dipping mechanism that a large number of work-holders can be employed and made to operate simultaneously to successively dip the articles carried by each work-holder into a series of baths.

A further object is to provide in a dipping apparatus an endless carrier for the work-holders and to so associate said carrier with a series of tanks and work-holder-elevating devices that the endless carrier can be utilized throughout its full extent of travel for moving the work-holders and causing the successive immersing of the work or articles to be plated into baths arranged under the carrier, whereby the complete process of plating and washing can be accomplished while the article carried by a holder is moving from a given starting-point until it returns to such starting-point.

A further object is to improve the general structure of a dipping mechanism and to so construct and arrange the various details thereof that the whole shall be strong and substantial, as well as accurate and efficient in operation.

With these objects in view the invention consists in certain novel features of construction and combinations and arrangement of parts, as hereinafter set forth, and pointed out in the claims.

In the accompanying drawings, Figure 1 is a side elevation, partly broken away, showing an embodiment of my invention. Fig. 2 is a plan view. Fig. 3 is a transverse sectional view on the line $x-x$ of Fig. 1. Fig. 4

is an enlarged sectional view through a portion of the carrier. Fig. 5 is an enlarged face view of a portion of the chain of the conveyor.

1 represents suitable framework, and 2 3 two endless carriers arranged horizontally 60 one above and spaced from the other. Each carrier passes around sprocket-wheels 4, secured to vertical shafts 5 at respective ends of the framework, and the shafts are provided with worm-wheels 6, receiving motion 65 from worms 7 on a driving-shaft 8. Arranged under the carriers throughout the full extent of the travel thereof, except at the loading and unloading point, is a series of tanks for containing the various plating and washing 70 baths employed in the art of electroplating.

The two endless carriers are identical in construction and operation, and a detail description of one will therefore suffice for both. The frame of each carrier comprises 75 two pairs channeled guides 9 10, the channeled or U bars of each pair being secured to the main framework and spaced apart, facing each other, as shown in Fig. 4. The two parallel pairs of channeled guides may be 80 braced by cross-bars 11, and the guides of one carrier will be connected with the guides of the other carrier by means of vertical angle-irons 12. The endless chain 13 of the carrier travels through the pairs of channeled guides 9 10 and around the sprocket-wheels 4. Each endless carrier-chain comprises a series of links 14, pivotally connected together by means of a pin. These links move through the pairs of channeled guides, 85 and the connecting-pins project beyond the edges of the links for the reception of rollers 16, which run against the inner faces of the guides and prevent undue lateral vibration of the carrier. The links of the carrier-chain 90 are also provided on each side with rollers 17, disposed between the opposing edges of the channeled guides of each pair and prevent undue vertical movement of the carrier. The rollers 16 and 17 thus serve to insure the easy 100 and straight running of the carrier between the sprocket-wheels 4. Each of the sprocket-wheels consists of two disks provided with peripheral notches to receive the rollers 16 on the links of the carrier-chain for transmitting motion to the latter.

Each link of each carrier-chain is provided in one face with two sockets or perforations

18 for the reception of pintles 19, adapted to project laterally between the channeled guides and beyond the same for the reception of grooved wheels 20. In practice only 5 certain of the links will be provided with the pairs of pintles 19 and grooved wheels 20; but all of said links will preferably be adapted for the reception of the pintles and grooved wheels, for reasons which will hereinafter appear. The pairs of grooved wheels 20 on the links of one carrier-chain will be arranged in line with the wheels 20 on the links of the other carrier-chain to receive and 10 guide vertically the movable rods or shanks 21 of work-holders 22. Thus it will be seen that the two carriers coöperate in moving the work-holders over the series of plating and washing baths. Between the two carriers cam-tracks 23 are secured to the framework, 15 and each work-holder rod is provided with a roller 24 to run on said cam-tracks. The cam-tracks are arranged to bridge the dividing-walls of the tanks, so that when the roller 24 of a work-holder rod reaches a cam-track 20 it will travel up one inclined member *a* thereof, so as to raise the work-holder and the work carried thereby out of a tank. Said roller 24 will then travel on the straight upper portion *b* of the cam-track until the work-holder has passed the dividing wall or space 25 between two tanks or baths, and then said roller will travel down the other inclined member *c* of the cam-track, (the angle of the member *c* preferably being more abrupt 30 than that of the inclined member *a* of the cam-track,) and thus cause the work to be immersed in the next tank or bath. It will of course be understood that a cam-track such as above described will be provided for 35 raising the work from each bath and automatically depositing it into the next.

By adapting all the links of the carrier-chains for the reception of guide-rollers 24 the spacing of the work-holders and the 40 tanks can be adjusted as desired. The various baths are provided with anode-plates, while the work constitutes the cathode, the latter being included in the electric circuit through the medium of the work-holder and 45 its rod or shank and conductor-strips 25 on the framework, said conductor-strips being provided with suitable brushes 26, which wipe against the rods or shanks of the work-holders.

50 Various changes might be made in the details of construction of my invention without departing from the spirit thereof or limiting its scope, and hence I do not wish to limit myself to the precise details herein set forth.

60 Having fully described my invention, what I claim as new, and desire to secure by Letters Patent, is—

65 1. In a dipping mechanism, the combination with an endless carrier and a series of work-holders movable thereby, of means for

automatically and independently raising and lowering each work-holder.

2. In a dipping mechanism, the combination with a carrier, work-holders and means for attaching a series of work-holders to the 70 carrier, of means for raising and lowering each work-holder independently of the others.

3. In a dipping mechanism, the combination with a carrier and a series of tanks under the same, of a series of work-holders connected with the carrier over said tanks, and means for independently raising each work-holder out of one tank and inserting it into the next. 75

4. In a dipping mechanism, the combination with a work-holder, of means for moving 80 the work carried by said holder through a bath, and means independently of the carrier for raising and then lowering said work-holder.

5. In a dipping mechanism, the combination with a work-holder of means for moving the work carried by said holder successively through a series of baths, and means independent of the carrier for raising the work-holder from one bath and depositing it into 90 the next bath.

6. In a dipping mechanism, the combination with a series of work-holders, of means for moving the work carried by said holders simultaneously through a series of baths and means for independently raising each work-holder from one bath and lowering it to the 95 next bath.

7. In a dipping mechanism, the combination with an endless carrier and a series of 100 work-holders carried thereby, of means for raising and lowering each work-holder independent of the others during the travel of the endless carrier.

8. In a dipping mechanism, the combination with superposed carriers, and a work-holder connected with both carriers, of means for raising and lowering said work-holder during the travel of the carriers. 105

9. In a dipping mechanism, the combination with superposed endless carriers, of a series of work-holders, each work-holder connected with both carriers and movable with said carriers throughout the full travel thereof, and means interposed between said carriers for moving the work-holders vertically. 115

10. In a dipping mechanism the combination with a carrier, and a work-holder attached thereto, of a cam, and a projection on the work-holder to ride on said cam to raise 120 and lower said work-holder.

11. In a dipping mechanism, the combination with two carriers, spaced apart, of a work-holder attached to both of said carriers, a cam located between the carriers and a projection on the work-holder to ride on said cam to raise and lower the work-holder. 125

12. In a dipping mechanism, the combination with two superposed carriers, of a work-holder carried by both of said carriers and 130

vertically movable relatively thereto, and means for moving said work-holder vertically relatively to the carriers.

13. In a dipping mechanism, the combination with an endless carrier, of grooved wheels carried by a link of said carrier, a work-holder having a part vertically movable between said grooved wheels and means for moving said work-holder vertically.

14. In a dipping mechanism, the combination with an endless carrier, of means for guiding said carrier, a work-holder having a part connected with and vertically movable relatively to said carrier outside of said guiding means, and means for moving said work-holder vertically.

15. In a dipping mechanism, the combination with an endless carrier comprising a series of connected links and means of driving the same, of guideways embracing said links, two grooved wheels projecting from a link of the carrier through the space between the guideways, a work-holder disposed between said grooved wheels and vertically movable relatively thereto, and means for moving said work-holder vertically.

16. In an apparatus of the character described, the combination with an endless car-

rier and a series of tanks located under the same, of a series of vertically-movable work-holders attachable to the carrier, means for independently moving each of said work-holders vertically, anode-plates disposed in the tanks, and means for including the work-holder in an electric circuit with the anodes and the baths in which they are immersed.

17. In an apparatus of the character described, the combination with a carrier, a series of tanks for plating-baths located under the carrier, and anode-plates in said tanks, of a series of vertically-movable work-holders, each having a shank connected with said carrier, an electric conductor-bar on the frame of the carrier, brushes electrically connected with said conductor and wiping against the shanks of the work-holder, and means for independently raising and lowering each work-holder.

In testimony whereof I have signed this specification in the presence of two subscribing witnesses.

DAVID FELIX BRODERICK.
